ABSTRACT

A Magazine Rack having a U-shaped back, rectangular support members and a spine secured to said support members. A substantially U-shaped presser member is pivotally connected to cross members secured to the spine and is spring biased against the front of the spine.

1 Claim, 4 Drawing Figures

FIG. 1

FIG. 2

1
MAGAZINE RACK**BACKGROUND OF THE INVENTION**1. **Field of the Invention**

This invention relates to a rack and more specifically to a magazine rack in which magazines are sturdily held in position.

2. **Description of the Prior Art**

Conventional magazine racks fulfill the object of being a receptacle for the placement of magazines, newspapers and sundry items. But the placement of these items heretofore has been deficient because the receptacle has no means whereby these items may be maintained in an orderly upright position for easy withdrawal and replacement without flopping.

Racks, which are constructed of bulky wood-type or other opaque materials, tend to obstruct views. These racks are also less durable because of the extensive use of nails, screws, and similar devices prone to displacement. Conventional wooden racks are more costly in production due to the extra materials and work involved in the staining, painting and finishing of the wood to compliment the decor of a particular room. But as aforementioned, the primary deficiency of the conventional rack is the lack of a means whereby contents may be held in a secure, upright, orderly position. The lack of this means not only hinders the orderly placement and removal of the rack's contents, but permits the magazines to fall toward the rear of the rack. Generally, those minority of racks in which it is possible to store items in some orderly fashion, are still limited because the magazines and such are stacked at the same height one behind the other, thus, obstructing the titles of the succeeding magazines. To pick out the desired item the whole stack must be examined. Therefore, it is desirable to have a magazine rack designed in such a way as to eliminate the aforementioned deficiencies of the conventional type magazine rack.

SUMMARY OF THE INVENTION

Accordingly it is an object of the invention to provide a rack which is light-weight, and capable of a variety of placement positions in a room, such as hanging on a wall, placing on a table or placing on a floor. Further, the invention provides a rack of greater durability and a means whereby magazines can be positioned and secured in an orderly upright fashion in the front of the rack allowing for easy detection of the particular magazine desired without disrupting the order of the other items therein placed.

Still further objects of this invention reside in a rack whereby the user may insert a magazine at the front of the rack. This invention is less cumbersome than conventional racks and is relatively inexpensive to manufacture.

These together with the various ancillary objects and features which will become apparent to those artisans possessing ordinary skill in the art and as the following description proceeds, are attained by this novel magazine rack a preferred embodiment shown in the accompanying drawings by way of example only wherein:

BRIEF DESCRIPTION OF THE DRAWING

FIG. 1 is a perspective view of a preferred embodiment of a magazine rack constructed of rigid wire in accordance with the invention.

2

FIG. 2 is a vertical sectional view taken along the plane of line 2-2 FIG. 1 illustrating part of the spine, the back and a down-biased spring connected to a follower member;

5 FIG. 3 is a top view of the preferred embodiment showing follower member, a rectangular support member, the back, and the front;

10 FIG. 4 is an entire cross-sectional view of FIG. 3 additionally showing a lower rectangular support member, the vase and the follower member pivotally connected to the spine.

DETAILED DESCRIPTION OF THE INVENTION

With continuing reference to the accompanying 15 drawing wherein like reference numerals designate simular parts throughout the various views, reference numeral 10 is used to generally designate a magazine rack having a rectangular support member 20 to which a U-shaped back is welded or otherwise attached. A 20 wire spine 15 of integral construction has a pair of rear members 28 and 50 which extend downwardly from the rectangular support member 20. The spine is strengthened by two cross members including an upper cross member 34 and a lower cross member 32 parallel to 25 each other and connecting across members 28 and 50. A substantial U-shaped presser member 38 having divergent wings 39 and 41 is pivotally connected to the lower cross member 32 and is engaged with at least one down-biased spring 36 which is mounted on upper 30 cross member 34 and lower cross member 32. The spring 36 urges the substantial U-shaped member 38 to contact the two front members 56 and 57 of the spine 15, which are interconnected by connected members 50. The front members 56 and 57 are forwardly arcuate, and are connected to members 28 and 59 by members 52 and 54.

A second rectangular support member 30 having its lowest side connecting to front member 56, and 57 and its highest side connecting to U-shaped member 22 and 40 rear member 28 and 50.

In operation magazines are inserted by merely lifting the presser member 38. After the magazines are inserted, the presser member will hold the magazines securely and in an upright position firmly at the front of 45 the rack. There will be no loose falling of individual magazines in the rack but all the magazines will be firmly urged by the presser member 38 toward the front of the rack. If a prospective purchaser were to remove 50 a magazine for inspection, the magazine may be easily reinserted because of the forwardly arcuated top configuration of members 56 and 57. The spring 36 is disposed opposite the approximate location of the spines of the magazines to be displayed in the magazine rack.

55 A plurality of the racks may be arranged against a supporting structure and held there by suitable fasteners extending through mounting plates 24. Of course the racks may be manufactured in multiples as desired.

A latitude of modification change and substitution is 60 intended in the foregoing disclosure, and in some instances some features of the invention will be employed without a corresponding use of other features.

What is claimed is:

1. A rack comprising a back, upper and lower rectangular wire support members connected to said back and extending downwardly and forwardly therefrom, said back including an upright U-shaped member having an open end closed by said upper support member,

a U-shaped spine open at the top including a pair of rear members extending downwardly from said upper support member and a pair of front members extending upwardly from a pair of members connecting said front and rear members and a connected member connecting said front members, said rear members being attached to the rear of said support members and said front members being attached to the front of said support members, said spine being located inwardly of said rectangular support members, and an upwardly and forwardly extending presser member pivotally con-

nected to said spine at the rear thereof, and spring means for urging said presser member against said spine at the front thereof, said spine including a pair of cross members, said presser member being pivotally mounted on one of said cross members, said presser member being located substantially inwardly of said spine and including two diverging wings at the front thereof, said wings being engageable with said spine, said spring means being disposed on said one of said cross members at one side thereof.
